UNITED STATES PATENT OFFICE

BARTON D. HUBBARD, OF PORTLAND, MAINE, ASSIGNOR TO BROWN COMPANY, OF
BERLIN, NEW HAMPSHIRE, A CORPORATION OF MAINE

YARN GUIDE FOR UPSTROKE TWISTERS

Application filed October 7, 1930. Serial No. 486,992.

This invention relates to upstroke twisting mechanism by which a cheese or cake of yarn is rapidly rotated while the yarn is fed from the interior of the cheese. The rotation of the cheese imparts a twist to the yarn, the amount of twist depending upon the relation between the rate of rotation and the rate of feed. Heretofore it has been customary to place the cheese of yarn in a rotatably mounted pot having a central spindle, the end of the yarn being led upwardly to a point above the spindle where it is engaged by feed rolls. Owing to the liability of the yarn to become twisted around the spindle and thus to cause the yarn to break, various devices have been made to overcome this tendency. According to the present invention the spindle is omitted entirely and a stationary guide is provided instead to lead the twisted strand from the pot and to prevent ballooning of the strand. To this end the tube may be advantageously supported with at least its lower end substantially in the axis of rotation of the pot. The tube is preferably adjustable vertically so that it can be correctly positioned relatively to the pot for satisfactory operation according to the speed of rotation of the pot, the size of the yarn, etc.

For a more complete understanding of the invention, reference may be had to the description thereof which follows and to the drawing in which,—

Figure 1 is a perspective view of an embodiment of the invention, other associated mechanisms being shown in elevation and section.

Figure 2 is a section on the line 2—2 of Figure 1.

As illustrated in Figure 1, the invention may include a pot 10 rotatably mounted on a spindle 11 which is provided with a pulley 12 to receive a driving belt in a manner well known in the art. The rotatable spindle 11 projects downwardly through a portion of a

fixed frame 13 in a manner well known in the art, a brake 14 being provided to stop the rotation of the spindle and pot quickly when desired. As shown, the pot is not provided with a central spindle rising from the bottom thereof. Instead, a suitable tube 20 may be supported above the pot as by a bracket 21 mounted on the frame 13. The tube 20 may be alined with the axis of rotation of the pot 10, the lower end 22 of the tube being adjusted at any desired height above the bottom of the pot 10. A set-screw 23 may be provided in the head of the bracket 21 to hold the tube 20 in adjusted position.

In order to facilitate the threading of the tubular guide 20, it may be provided with a lateral slot 25 extending from one end to the other thereof, this slot being cut through the wall of the tube, as shown in Figure 2, in a direction at an angle to the radius of the tube. As shown, the direction of the slot is nearly tangent to the inner surface of the tube. The lower end 22 of the tube is rounded so as to prevent the catching or chafing of yarn thereon. The non-radial direction of the slot 25 prevents the yarn from catching at the lower end of the slot. The head of the bracket 21 may also be provided with a slot 26 with which the slot 25 is made to register so that the yarn can be quickly threaded through the tube 20. The lower end 22 of the tube serves as a circular guide to lead the twisted yarn from the interior of the pot. The walls of the tube above the lower end act to prevent ballooning of the twisted yarn above the mouth of the pot.

The yarn, after leaving the tube 20, may be led through a suitable upper guide 30 and thence to a pair of feed rolls 31, 32, one of which is driven in the usual manner, and thence through a traversing guide 33 to a bobbin or spool 34 on which it is wound into a thread body by a suitably driven roll 35 on which the spool 34 rests.

It is obvious that various changes and

modifications may be made in the structure shown and described without departing from the spirit and scope of the invention.

I claim:

5 In an upstroke twister, a rotatable pot, and a tubular yarn guide having its lower end in the axis of rotation of said pot, said tubular guide having a lateral slot through its wall at an angle to the radius of the tube and extending from one end of the tube to 10 the other.

In testimony whereof I have affixed my signature.

BARTON D. HUBBARD.
